ATTORNEY

UNITED STATES PATENT OFFICE

HENRY J. GAISMAN, OF NEW YORK, N. Y., ASSIGNOR, BY MESNE ASSIGNMENTS, TO GILLETTE SAFETY RAZOR COMPANY, OF BOSTON, MASSACHUSETTS, A CORPORATION OF DELAWARE

SAFETY RAZOR

Application filed October 19, 1927. Serial No. 227,109.

My invention relates to improvements in safety razors of the class in which a rotatable or rockable blade holder is operated by means of a roller that is adapted to be rotated in contact with a surface when the razor is reciprocated for causing opposite sides of the blade edge to be drawn along a stropping surface for stropping or sharpening said edge.

10 An object of my invention is to provide a safety razor in which the guard is adapted to be moved forwardly through the frame from behind the shaving position of the blade to be presented in shaving position 15 with respect to the blade, and whereby both the guard and the blade with its holder may be folded within the main frame of the razor for storage and transportation.

Another object of my invention is to provide means for pivotally supporting a guard for the blade in such a manner that the pivots of the guard will be movable respecting the blade, whereby to allow the guard to adjust itself to the blade.

25 My invention comprises novel details of improvement that will be more fully hereinafter set forth and then pointed out in the claims.

Reference is to be had to the accompanying drawings forming a part hereof, wherein

Fig. 1 is a perspective view of my improved razor;

Fig. 2 is a front elevation looking from the left hand side of Fig. 1;

Fig. 3 is a vertical section through Fig. 1;

Fig. 4 is a detail view illustrating the parts in shaving position;

Fig. 5 is a sectional view illustrating the parts in folded position;

Fig. 5a is a sectional view illustrating the parts released for stropping the blade edge;

Fig. 6 is a detail view of the blade holder;

45 Figs. 7 and 7a are sections on line 7, 7, of Fig. 6, showing the parts in different positions, and

Fig. 8 is a side view illustrating the razor in stropping position.

Similar numerals of reference indicate 50 corresponding parts in the several views.

The numeral 1 indicates the main frame of the razor which is shown comprising a base 1a and spaced uprights 1b. A handle 2 may be attached to the base in any well known or desired way. At 3 is a blade holder for a blade 4. The blade holder is pivotally supported between the uprights 1b and is shown provided with pivots 5, 5a journaled in holes in said uprights. The pivot 5 is shown provided with a gear 6 60 that is in mesh with a gear 7 secured to a roller 8 whose end portions 8a serve as pivots are journaled in holes in the uprights 1b. The periphery of the roller 8 extends beyond the adjacent portion of the uprights 65 1b in such a way that said roller may rest upon a surface 9, (Fig. 8), so that when the razor is reciprocated along said surface the roller will be rotated, whereby its gear 7 will cause rotation of the gear 6 for rotating or rocking the blade holder and the blade for stropping purposes.

The blade holder illustrated comprises a plate-like member 3a upon which is hinged a blade retaining member 3b by means of a hinge at 3c. The plate 3a is shown provided with spaced projections 3d adapted to pass through spaced holes 4a in blade 4 to retain the latter in proper shaving position within the holder. Means are provided to 75 retain the blade holder members 3a and 3b clamped against the blade, for which purpose I have shown the member 3b provided with a catch 3e adapted to pass through a hole 3f in member 3a to resiliently engage 85 an edge of the hole to retain the parts clamped, as in Fig. 7. When the blade is to be released and replaced the member 3b will be swung away from the blade, as illustrated in Fig. 7a.

At 10 in a guard for the blade edge, which may be of any suitable or usual construction for cooperation with the blade. Said guard is shown provided with arms 10a adjacent to its ends, which are pivotally supported at 11 upon the outwardly or laterally extending end portions 12a of a flat spring 12. The central portion of the spring is secured to the frame which may be accomplished by riveting the stud 2a (attached to or formed 90

with the handle 2) over the spring. The portion 12a of spring 12 on opposite sides of the stud 2a curves laterally in the direction of the blade holder, so that the pivots of the 5 guard may have movement, under the tension of the spring, with respect to the blade. At 13 is a spring shown located between the base 1a of frame 1 and spring 12, which spring 13 may be retained by the stud 2a, (Fig. 2). The 10 end portions of spring 13 are located at a distance from base 1a and are cooperative with the corresponding end portions of the arms 10a of the guard. Said arms are shown provided with a side portion 10b adapted to 15 operate with spring 13 to retain the guard in shaving position, (Fig. 3), and with a relatively flat portion 10c to cooperate with spring 13 when the guard and the blade are folded within the frame 1, (Fig. 5), and said 20 arms are provided with relatively flat portions 10d to cooperate with spring 13 to retain the guard away from the blade with the parts in position for stropping the blade edge, (Fig. 5a). The guard 10 is provided with 25 one or more projections 14 adapted to engage a corresponding projection or stop 15 on the blade holder, whereby when the guard and the blade holder are in shaving position said 30 projections will engage and retain said parts, as illustrated in Figs. 3 and 4.

The relation of the parts is such that the guard is movable behind the blade and the blade holder, within frame 1, from the shaving position, (Fig. 3), to the folded or storage position of the blade holder and guard, as illustrated in Fig. 5, and reversely. When the guard is to be adjusted to the blade the guard will be pushed toward the left in Fig. 5, through the frame, with the guard bearing 40 against the blade holder to swing the latter forwardly, to bring the projections 14 and 15 into cooperation, and at such time the tension of the spring 13 against the arms 10a of the guard will retain the parts in shaving position with the blade edge in proper relation to the guard. When the blade is to be stropped the guard will be swung outwardly from the frame and will be retained by spring 13, as in the position shown in Figs. 5a and 8. A 45 finger piece 16, which may be stamped out of the metal of the guard, enables convenience in manipulation of the latter.

To retain the blade holder in the folded position a latch 17 is pivotally supported at 50 18 upon one of the uprights 1b, between the latter and the adjacent arm 10a of the guard, (Fig. 2). Said latch is adapted to engage a projection or pin 19 on one of the arms 10a of the blade holder, (Fig. 2). The end portion 17a of the latch 17 is adapted to engage 55 spring 13 when the parts are in the position shown in Figs. 1, 2, 3 and 5, whereby to retain the latch against a strop pin 20 on the adjacent upright 1b. The opposite end portion 60 of latch 17 is inclined at 17b so that the adjacent 65 portion of the blade holder may ride thereagainst and may be caught in the depressed portion 17c of the latch when the blade holder is in folded position to retain the blade holder, as illustrated in Fig. 5. The inner edge of latch 17 is curved at 17d in position to be engaged by the projection 19, the relation of the parts being such that when the guard is pushed to shaving position the projection 19 will advance and permit latch 17 to tilt to release the blade holder, (Fig. 3), and when the guard is moved outwardly to stropping position, as indicated in Fig. 5a, the projection 19 will engage the latch from the lower side of pivot 18 to cause tilting of 70 the latch out of the path of the blade holder, so that the holder and the blade will be free to swing through the frame for stropping purposes.

When the blade is to be stropped the parts will be set in the positions shown in Figs. 5a and 8, whereupon the razor frame will be held in such a position that the roller 8 will bear upon the surface 9, and as the razor is reciprocated along said surface the holder and blade will be rotated or rocked for stropping the blade edge, the roller and the gearing causing the blade edge to drag behind the razor along the stropping surface, and at each termination of a reciprocation of the razor and upon the reverse stroke the blade will be rocked and a different side of the edge presented to the stropping surface.

My invention is not limited to the details of construction set forth, as the same may be varied, within the scope of the appended claims, without departing from the spirit of my invention.

Having now described my invention what I claim is:

1. A safety razor comprising a frame, a blade holder pivotally carried by the frame to swing therethrough, means to cause the holder to swing through the frame for stropping a blade, a guard pivotally carried by the frame and adapted to swing within the frame beneath the blade holder and the blade, said guard and blade holder having cooperative means to engage when the guard has been moved within the frame under the blade holder to shaving position, and means to retain the guard and blade holder in shaving relation.

2. A safety razor as set forth in claim 1, in which the means to engage the guard and the blade holder comprise projections from the guard and blade holder adapted to engage when said parts are in shaving position.

3. A safety razor comprising a frame, a blade holder pivotally carried by the frame to swing therethrough, a guard pivotally carried by the frame and adapted to swing beneath the blade holder and the blade, said guard and blade holder having cooperative means to engage when the guard has been

5 moved under the blade holder to shaving position, said means including a projection on the underside of the blade holder and a projection on the guard to engage the first named projection when the guard and the blade holder are in shaving relation, and means to retain the guard and blade holder in shaving relation.

10 4. A safety razor as set forth in claim 1, in which the means to retain the guard and the blade holder comprises a spring carried by the frame and having free ends, and in which the guard is provided with relatively flat portions to engage the spring to retain the guard in set positions.

15 5. A safety razor comprising a frame, a blade holder carried thereby, a guard for a blade edge, and resilient means pivotally supporting the guard to have movement relatively to the blade holder to permit the guard to adjust itself with respect to the blade.

20 6. A safety razor as set forth in claim 5, in which the means that pivotally supports the guard comprises a spring carried by the frame and having portions at a distance from the frame pivotally supporting the guard to permit the latter to adjust itself respecting the blade holder.

25 7. A safety razor as set forth in claim 5, in which the means that pivotally supports the guard comprises a spring carried by the frame and having free end portions provided with inwardly extending members, the blade holder being pivotally supported upon said members.

30 8. A safety razor comprising a frame, a blade holder carried thereby, a guard for a blade edge, a spring carried by the frame and having inwardly extending end portions, the guard being pivotally carried by said end portions, whereby the guard may adjust itself with respect to the blade holder, and a spring located between the frame and the first named spring and adapted to cooperate with the blade holder to retain the latter in set positions.

35 9. A safety razor comprising a frame, a blade holder pivotally carried thereby adapted to swing through the frame, a guard pivotally carried by the frame adapted to swing therethrough, means to retain the guard and blade holder in shaving relation, a latch carried by the frame having a portion adapted to engage the blade holder to retain the latter in folded position within the frame, spring means to retain the latch in blade holder retaining position, and means cooperative with the guard and the latch to swing the latter out of blade holder retaining position when the guard is moved out of the frame for stropping position of a blade.

40 10. A safety razor as set forth in claim 9, in which the latch is provided with an end portion adapted to be engaged by the blade

45 holder when the latter is moved to folded position within the frame, said latch having a curved edge, the guard having a projection to engage said curved edge of the latch to move the latter from blade holder retaining position when the guard is swung outwardly to blade stropping position.
